FLOUR SIFTER

Richard B. Cronheim, St. Louis, Mo.

Application June 19, 1959, Serial No. 56,426

Term of patent 14 years

(Cl. D44—29)

FIG. 1

FIG. 2

FIG. 3

FIG. 4

FIG. 5

Fig. 1 is a right-hand side elevational view of a flour sifter embodying my new design;

Fig. 2 is a front elevational view thereof;

Fig. 3 is a rear elevational view thereof;

Fig. 4 is a left-hand side elevational view thereof; and

Fig. 5 is a top plan view thereof.

I claim:

The ornamental design for a flour sifter, substantially as shown.
